UNITED STATES PATENT OFFICE.

JAMES H. A. CARR, OF MCKEES ROCKS, PENNSYLVANIA.

DESIGN FOR A COMBINED MICROSCOPE AND MIRROR.

59,579.

Specification for Design.

Patented Nov. 8, 1921.

Application filed November 22, 1920. Serial No. 425,922. Term of patent 14 years.

To all whom it may concern:

Be it known that I, JAMES H. A. CARR, a citizen of the United States, residing at McKees Rocks, in the county of Allegheny and State of Pennsylvania, have invented a new, original, and ornamental Design for a Combined Microscope and Mirror, of which the following is a specification, reference being had to the accompanying drawing, forming part thereof.

The figure is a perspective view of a combined microscope and mirror, showing my new design.

I claim:—

The ornamental design for a combined microscope and mirror, as shown.

JAMES H. A. CARR.
